PACKAGING AND DISPLAY CONTAINER

Champe S. Andrews, North Chattanooga, Tenn.,
and Arnold J. Tanner, North Haven, Conn., as-
signors to Box Blank Corporation, New York,
N. Y., a corporation of Delaware

Application September 24, 1931
Serial No. 564,808

9 Claims. (Cl. 206—44)

This invention relates to containers useful for packing and displaying merchandise and the improved container made according to said invention is designed to meet practically all requirements for an efficient, economical and simple container for merchandise of various kinds.

The container comprises several parts and these parts may be employed wholly or in part to meet different requirements. The improved container is composed of an outer shell or body having a front wall, a back wall and side walls forming a tubular structure. An inner member provides a reinforcement or inner back wall for the outer body member.

In one embodiment of the invention, the inner member carries means for closing the bottom of the container, and in another embodiment of the invention, the shell or outer body member of the container carries the bottom closing means. In both instances the inner back-

ing member carries a folding flap which is employed to cover the top of the box when the latter is in closed position, and when the box is open said flap is employed as a display card. The flap is connected to the backing sheet of the inner member at a point which is defined by a creased line and the flap hinges about the creased line. When the inner member is properly located within the outer member the creased line will lie just below the top edge of the back wall of the outer member so that the flap, when raised, will be retained in a position substantially in alignment with the back wall of the container. The erect position of the aforesaid display card is maintained by the top edge of the back wall operating as a stop or abutment therefor.

In one form of the invention the inner member carries the means for closing the bottom of the container, in which case a closure flap extending from the lower edge of the body member is provided. This flap is retained in place by a tuck-in fold provided thereon. In another form the bottom closure flaps are provided directly on the body member. The container may be supplied to the customer in assembled condition, in which case the inner member is secured to the body member by adhesive staples or the like at the box factory. Where the blanks are furnished separated from each other, a convenient uniting means is provided so that the said members may be united by hand operation by the user so as to eliminate the necessity of gluing or machine operation. Where the bottom closure means is carried by the inner mem-

ber, simple means are provided whereby the bottom may be partly pulled down so as to provide a base to support the container in an inclined or backwardly leaning position.

The several embodiments of the present invention will be more fully described hereinafter with reference to the accompanying drawings, wherein

Figure 1 is a perspective view showing the improved container standing in the open or display position;

Figure 2 is a longitudinal sectional view of the improved container;

Figure 3 is a longitudinal sectional view showing a modified form of the container;

Figure 4 is a longitudinal section of a telescoping cover suitable for both forms of the container;

Figures 5 and 6 are plan views of a pair of blanks employed for constructing the box illustrated in Figure 3; and

Figures 7 and 8 are plan views of another pair of blanks employed in the construction of the container illustrated by Figures 1 and 2.

Referring to both forms of the container shown herein, the selected blank A or B is folded to form a collapsible structure constituting the outer member or body of the container having a front wall 1, a back wall 2, and side walls 3. The said blanks are creased as represented by broken lines *a* and *b* to divide the blanks into sections forming said walls of the container. In the first operation of manufacture, the blanks are folded so as to bring the gluing strip 4 over the opposite or free edge of the blank where it is adhesively secured. This operation of folding and gluing can be performed by any suitable machine of a standard type. The body so formed is collapsible and when set up is of a tubular form having an open top and bottom, means being provided to close the open bottom.

To form the container shown in Figure 3, blank A is used. The means for closing the bottom comprises flaps 5 depending from the different sections in the blank and these flaps are adapted to be folded and glued by machine operation, if desired. Any other known and suitable form of bottom closure device may be employed if desired, particularly when the box is to be assembled by hand operation without gluing.

In both embodiments of the invention, an additional blank A' or B' is employed and the selected blank is secured on the inside of the back wall of the container. In the embodiment of the invention shown in Figure 2, the blank A' is secured

to the back wall of the container by suitable means, as for example, by gluing. A folding flap 6 extends upwardly from the blank A' and is adapted to hinge on said crease line c. The inner member is precisely located so that the crease line c lies just below the top edge d of the back wall of the container. The flap 6 provides a cover for the open top of the container when it is in its closed position and when the container is open, said flap 6 operates as a display card standing erect at the back of the container. It is desirable, in order to get the best effect, that the flap or show card 6 should stand in a position substantially in alignment with the back wall of the container. To maintain the display device in aligned position, the crease line on which the flap 6 hinges is dropped below the top edge of the back wall of the container, as stated, so that the portion of the top edge lying above the crease operates as a stop or abutment against which the flap will strike so as to prevent it from folding backwardly beyond the desired point.

Referring now particularly to the container shown in Figures 1 and 2, the inner or back wall reenforcing member B' comprises a backing sheet, shown in Figure 8, which carries the folding display card or cover flap 6. Inner member B' also carries means for closing the bottom of the container, comprising the flap 7 having the insert extension 8 which is arranged to be tucked into the container to retain the closing flap in place. Auxiliary means for closing the bottom comprises extensions 9 projecting from the side walls 3 of the outer member. Extensions 9 are arranged to fold inwardly so as to assist in closing the bottom and to provide additional frictional means for engaging the tuck-in end 8 of the closure flap 7. The backing sheet is secured to the back wall 2 of the container by suitable means. When the outer and inner members are joined together at the factory where the boxes are made, they may be conveniently joined together by stapling or gluing. In such cases where the packer has to unite the two members together, convenient means are provided for this purpose, which may comprise a circular hole 10 provided in the inner member B' which will register with tabs 11 cut out of the back wall of the outer blank B. To assemble, the tabs 11 are inserted into the hole 10 as shown in Figure 2. This connection securely fixes the members in a definite relation which is maintained when the box is in use.

In both examples shown the front wall of the container has an opening cut therein through which the merchandise within the container may be viewed. Through this opening the securing connection 10-11 can also be conveniently manipulated.

It is often desirable to position a display container in an inclined position so as to get the best display effect. The bottom closure flap may be easily adjusted so as to operate as a base to support the container in an inclined position. The adjustment is effected by partially pulling out the tuck-in end 8 and then engaging the tab 12 cut therein with the bottom edge of the front wall. The container will then stand in the inclined position shown in Figure 1.

Containers made in the manner above described offer numerous advantages. The blanks for the container may be cut out with comparatively little waste of material. Another advantage is that the blanks may be composed of material prepared and printed on one side only, and when assembling the inner member is so placed

that the printed side will be exposed thereby presenting a prepared surface at the back of the container which is visible when the container is partly empty.

Various modifications may be made in carrying out the details of the invention hereinbefore described and it is to be understood that any modification coming fairly within the terms of the appended claims shall be covered thereby.

We claim:

1. A container comprising a body having front, back and side walls, bottom forming flaps on said body and a backing sheet secured on the inner surface of said back wall, said sheet carrying a closure flap for the top of the container, said flap being connected to said sheet so as to hinge on a transverse crease line, said top closure flap being adapted to operate as a display card when in an erect position, and said sheet being precisely located in a position wherein said crease or hinge lies below the top edge of said back wall so that said edge will operate as a stop to maintain said flap in an erect display card position substantially in alignment with said back wall.

2. A container comprising a body having front, back and side walls, a re-enforcing inner backing sheet mounted on the inner surface of said back wall, said sheet having a hinged flap operating as a display card, the hinge for said flap being located below the top edge of said back wall in a position so that said top edge will operate as a stop or abutment to maintain said display card in erect display position substantially in alignment with the back wall, said sheet having means adapted to engage said body to support the same in inclined display position.

3. A container comprising a body having front, back and side walls, an inner backing sheet mounted on said back wall, said backing sheet having a hinged flap extending above said back wall, the hinge for said flap being located below the top edge of said back wall so that said edge will operate as a stop or abutment to maintain said flap in an erect position, said sheet having means adapted to engage said body to retain the same in inclined display position.

4. A container of the class described comprising an outer body having a back wall, a re-enforcing backing sheet secured to the inner surface of said back wall, said backing sheet having connected thereto a folding flap extending above the top edge of said back wall, said flap being adapted to fold on a crease located below said top edge whereby said edge operates as a stop to maintain said flap in an erect position, said sheet having means adapted to engage said body to adjustably support the same in inclined display position.

5. A container of the class described comprising a collapsible tubular body having front, back and side walls, a backing sheet secured on the inner surface of said back wall, bottom closure means extending from said backing sheet and forming a support for the container in the set up condition, said backing sheet having a folding extension adapted to be utilized as a display card extending from said back wall, said display card being hingedly connected to said backing sheet, and the hinge for said card being located below the top edge of said back wall so that said top edge will operate as a stop to maintain said card in an erect display position.

6. A container comprising a body having front, back, side walls and an open top and bottom, an inner backing sheet secured to said back wall,

- 5 said backing sheet having a portion adapted to support said body when set up in display position, said backing sheet having a flap extending from and hinged to said backing sheet, said flap in its closing position covering the open top of the container, said flap in its erect position providing a display card extending upwardly from said back wall, and the hinge for said flap being located below the top edge of said back wall so that said edge operates as a stop to maintain said display card in set up display position.
- 10 6. A container comprising a body having front, back, side walls and an open top and bottom, an inner backing sheet secured to said back wall, said backing sheet having a portion adapted to provide a bottom for the container and a support for the body when set up for display, a flap extending from and hinged to said backing sheet, said flap in its closed position covering the open top of the container, said flap in its erect position providing a display card extending upwardly from said back wall, the hinge for said flap being located below the top edge of said back wall so that said edge operates as a stop to maintain said flap in set up display position, said front wall having an opening therein and said backing sheet extending substantially the full length of said back wall so as to present a printed surface visible through said open front wall when said container is partly emptied.
- 15 7. A container comprising a body having front, back, side walls and an open top and bottom, an inner backing sheet secured to said back wall, said backing sheet having a portion adapted to provide a bottom for the container and a support for the body when set up for display, a flap extending from and hinged to said backing sheet, said flap in its closed position covering the open top of the container, said flap in its erect position providing a display card extending upwardly from said back wall, the hinge for said flap being located below the top edge of said back wall so that said edge operates as a stop to maintain said flap in set up display position, said front wall having an opening therein and said backing sheet extending substantially the full length of said back wall so as to present a printed surface visible through said open front wall when said container is partly emptied.
- 20 8. A container comprising a collapsible tubular body having front, back, and side walls, closure means for the bottom of the container, an inner backing sheet secured to said back wall, said front wall having an opening therein, said backing sheet extending substantially the full length of said back wall, said backing sheet providing a re-enforcement for the container and a display surface visible through said opening in the front wall, said backing sheet having a folding flap extending therefrom, said folding flap operating as a cover in its closed position and as a display card in its open position, means for retaining said flap in its display position, and an outer shell arranged to slide over said container to completely close and re-enforce said container so as to render it suitable for shipping purposes.
- 25 9. A container of the class described comprising a body having back, side and front walls and an open top, a re-enforcing backing sheet or inner member secured to said back wall, said backing sheet having closure means forming a bottom for the container, said closure means being adjustable, and means for retaining said closure means in adjusted position so as to provide a relatively inclined bottom whereby the container is supported in an inclined display position.
